UNITED STATES PATENT OFFICE.

MARY M. MADDEN, OF ST. LOUIS, MISSOURI.

GARBAGE-CAN COVER HOLDER.

Application filed August 9, 1926. Serial No. 128,061.

My invention relates to garbage cans, and more particularly to a garbage can cover holder.

The object of my invention is to provide a garbage can having a cover with means for holding the cover from becoming detached, or separated from the can and for holding the cover in contact with the side wall of the can when removed from the top thereof, thereby preventing the cover from becoming mislaid, lost, or damaged after removal from the top of the can, which loosening and damaging of the can cover is a great annoyance with the present type of garbage cans.

A further object of the invention is to provide a garbage can cover holder which possesses advantages in points of simplicity and efficiency, and, at the same time proves itself comparatively inexpensive in point of manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a perspective view of a garbage can embodying the features of my invention.

Fig. 2, is a top plan view thereof with the cover removed from the top thereof and supported by the cover holder.

Fig. 3, is a vertical sectional view of the garbage can showing the cover supported by the cover holder.

Referring to the drawings, the reference numeral 1 represents the usual cylindrical type of garbage can for domestic use having the carrying bail 2 and provided with the usual dome shaped cover 3 having the can engaging flange, or rim 4. The flange 4 is provided with a suitable opening 5 through which passes a suitable cover guide member 6.

The cover guide member 6 which is vertically disposed, is suitably fixed to the side wall of the can 1 near the upper edge thereof and fixed at its lower end to the wall of the can near the lower edge of the can 1.

The cover guide member 6 has the inwardly directed upper leg section 7 and the lower

inwardly directed leg section 8 for holding the supporting member 6 in spaced parallel relation with the wall of the can, as is evident from Fig. 3. The upper end leg section 7 of the vertically disposed supporting member 6 is shown as passing through the wall of the can and then bent, as at 9, to engage the inner face of the can to which it is fixed by suitable fastening means. This arrangement permits the flange 4 of the cover 2 to snugly fit over the upper edge of the can so as to prevent, as nearly as possible, any of the obnoxious odors escaping from the can, when the cover 2 is in a closed position upon the can.

A cover supporting member 10 is suitably fixed such as by rivets, or similar fastening devices, at each end, to the wall of the can 1 at a suitable point intermediate the upper and lower edges of the can 1. The cover supporting member 10 is U-shaped and is fixed to the wall of the can in such a manner as to be disposed in a horizontal position and at right angles to the vertically disposed guide member 6, as clearly shown in the drawings. It will be observed that the U-shaped cover supporting member or band 10 passes the vertically disposed member to the outer face thereof and is spaced a suitable distance therefrom so as to act as a rack to engage the domed top of the cover when the cover is removed from the top of the can and allowed to slide down the guide member 6 to the lowermost end thereof.

The horizontally disposed cover embracing member associated with the vertically disposed guide member serves to provide a skeleton pocket to receive the lower portion of the cover when it is removed from the top of the can and disposed edgewise to the side thereof to prevent lateral or backward displacement of the cover and hold it at a substantial right angle to its closed position.

From the foregoing description, it is evident that a can provided with the cover holding means shown in the drawings will prevent the cover from becoming detached from the can which detachment usually results in the misplacement of the cover, the loss thereof, or damage thereto.

The many advantages of the herein described invention will readily suggest themselves to those skilled in the art to which it appertains.

I do not wish to be understood as having limited myself to the details of construction

shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes or modifications as may fairly fall within the scope of the appended claims when fairly construed.

What I claim is:

1. In combination, a garbage can, a cover therefor having an upwardly curved crown and a flange embracing the outer face of the can and said flange provided with an opening, a vertically disposed guide member passing through the flange opening and fixed at opposite ends to the wall of the can and arranged in spaced parallel relation therewith, a horizontally disposed U-shaped supporting member fixed at opposite ends to the wall of the can on opposite sides of the wall thereof with the midway portion thereof spaced from the outer face of the vertically

disposed guide member to provide a skeleton pocket to receive the lower half portion of the cover and support it in an edgewise position when removed from the top of the can by engaging the crown of the cover. 30

2. In a garbage can structure, a cylindrical open top can, a cover having curved crown and a flange fitting over the top of the can and said flange having an opening therein, a vertically disposed guide member 35 passing through said flange opening and fixed at its ends to the can by passing through an opening in the wall thereof and being bent over and riveted thereto and a horizontally disposed U-shaped cover crown 40 embracing member fixed at opposite ends to opposite sides of the can and having its midway portion spaced from the outer face of the vertically disposed guide member so as to supportingly engage the crown of the 45 cover when in an open edgewise position.

Signed in the city of St. Louis and State of Missouri, June A. D. 1926.

MARY M. MADDEN.
